[57] **CLAIM**

The ornamental design for a tire tread, as shown and described.

DESCRIPTION

FIG. 1 is a perspective view of a tire tread showing my new design, it being understood that the tread pattern is repeated throughout the circumference of the tire tread; FIG. 2 is a front elevational view thereof; and FIG. 3 is a side elevational view thereof.

The broken lines in the drawing are for illustrative purposes only.

FIG. 1

FIG. 3

FIG. 2
